UNITED STATES PATENT OFFICE.

CHARLES WALKER JONES, OF JOHNSONVILLE, MISSISSIPPI.

RAILWAY-CAR.

SPECIFICATION forming part of Letters Patent No. 426,385, dated April 22, 1890.

Application filed August 21, 1889; Serial No. 321,540. (No model.)

To all whom it may concern:

Be it known that I, CHARLES WALKER JONES, a citizen of the United States, residing at Johnsonville, in the county of Sun Flower and State of Mississippi, have invented certain new and useful Improvements in Railway-Cars; and I do hereby declare the following to be a full, clear, and exact description of the invention, such as will enable others skilled in the art to which it appertains to make and use the same.

This invention has relation to certain new and useful improvements in railway freight-cars, and more particularly to such as are known as the "gondola" or flat-bottom platform-cars.

The general object of my invention consists in providing cars of the above description with a false or transferable top, which top or truck shall be so constructed as to permit of its being shifted or transferred, together with the load thereon, from one car to another, or from the car to a platform built for the purpose beside the track, or which shall allow of the load being dumped direct from the car proper without necessitating the removal of the false platform-top from the car; and my invention further consists in the means whereby the false top may be securely retained in position during transit, whereby the same may be allowed lateral movement for dumping purposes, and, further, whereby the slipping or rolling off of the same when being shifted from side to side of the car is prevented.

With these objects in view my invention consists of the peculiar construction and arrangement of parts, as hereinafter more fully shown in the drawings and described in the specification.

Referring to the drawings forming a part of this specification, Figure 1 is a perspective view of a car provided with my improved transferable top, said top being in position to receive a load; Fig. 2, a view showing the false top run upon a side platform. Fig. 3 is a bottom plan view of the transferable top or car-truck; Fig. 4, a similar view of the car proper; Fig. 5, a detail view showing one of the operating-rod, with hand-wheels secured thereto; and Fig. 6 is a view showing the transferable top raised to a dumping position, so as to

more fully illustrate the means whereby the same is retained upon the car proper.

Similar letters of reference are used to designate corresponding parts throughout the entire specification and several views of the drawings.

The letter A is used to indicate the ordinary railway platform-car, to the top of which is secured the iron tracks a a', said tracks running crosswise to the length of the car and at suitable intervals apart. The end cross-tracks a a are made of half-round iron or steel, while the intermediate ones a' a' are of flat iron.

To both sides of the car I attach the keepers b b, within which the lower end of the standards B B are secured.

Beneath the car proper run the operating-rod C C', which are supported throughout their entire length by means of the hangers C' C', attached to the car-bottom at suitable intervals. The ends of the operating-rod project beyond the ends of the car, and have immovably secured thereon the hand-wheels D D'. The outer peripheries of these wheels have a series of holes d d formed therein, for the purpose hereinafter more fully stated.

The transferable top or car-truck is represented by the letter E, and consists of the metallic frame composed of longitudinal and cross-beams E' E'', which intersect each other at right angles, and to which is secured the floor or top E'.

To the bottom or beams of the false top I secure, within bearings e e, the rollers or wheels F F', which are adapted to work upon the tracks a a'. The outer periphery of the end wheels is grooved, so as to receive the tracks a a, while the intermediate wheels have flat surfaces, so as to roll upon the flat cross-tracks a' a'. By having the end wheels grooved to receive the half-round tracks at the end of the car-top, I am enabled to provide against the liability of one end of the false top running ahead of the other when being moved off the car, which would be liable to result if the end tracks were made of flat iron.

The top of the transferable truck, at the ends thereof, has opening e' e' formed therein, which register with openings f f in the car-bottom proper. Through these openings I

insert the retaining-bolts G, which serve, in conjunction with the standards B B, to securely hold the transferable truck in position during transit. The retaining-bolts G project beyond the bottom of the car and are keyed thereunder. The rollers or wheels secured in bearing beneath the transferable truck are in three rows, which rows are located beneath the sides and center of the platform. The platform or truck is sufficient in size to entirely cover the car proper, and the sides of the floor E³ have a series of notches h h formed therein, through which the standards B B pass.

15 Secured beneath the car proper to the operating-rod C C² are four chains H H', two of which are attached to each of the rods. The chains run from the operating-rod over the pulleys or rollers h' h', journaled in the 20 sides of the car beneath the floor and beams of the transferable truck until the opposite sides thereof are reached, where they are fastened to hooks j j, secured to the side of the trucks. By means of these chains, through 25 the medium of the operating-rod, I am enabled to shift or roll the car-truck from one side of the car to the other, so as to permit of the same being unloaded.

At each end of the car proper I fasten the 30 chain J, which is connected to the ends of the car-truck, at the center thereof, by means of the hook l, secured to its free end, which fits in the staple m. These chains are in length one-half the width of the car, and the 35 purpose thereof is to prevent the truck from rolling off when being dumped, as shown in Fig. 6 of the drawings.

In order to facilitate the turning of the operating-rod C C², I secure to the projecting ends thereof the hand-wheels D D', which, as before stated, are immovably fastened to said rods and have a series of openings or holes formed in their outer periphery.

Within the holes or openings d d fit the end 45 of the hand-lever L, by means of which the same is revolved and therewith the operating-rod.

The retaining-bolts G having been removed, the operation of dumping my improved transferable truck is as follows: The turning of 50 the hand-wheel D' revolves the operating-rod C², which causes the winding of the chains H' upon said rod, and as said chains are secured to the truck the latter is caused to move toward 55 the side of the car, moving upon the tracks a a' until the center rollers reach the same, when further lateral movement is stopped by reason of the chains J J, secured to the ends, at the center, of the car and truck. The truck 60 having moved sidewise until the center rollers reach the side of the car proper, which causes one-half the width of the truck to project beyond, the projecting weight will be sufficient to cause the tilting of the truck with 65 little or no pressure until the contents thereof have been emptied upon the ground, when by turning the hand-wheel D, which revolves the

operating-rod C, causing the winding of the chain H thereon and loosening of chain H' from rod C², the truck is brought back to its 70 original position. When the freight to be unloaded consists of heavy material—such as stone, iron, &c., or such as would be liable to break if dumped from the car—it then becomes necessary that the truck and loaded 75 freight be run or transferred to the platform O, built to the side of the track, provided with tracks corresponding with those upon the car-top, as shown in Fig. 2 of the drawings. In order to transfer the false top or truck to the 80 platform, the chains J J should be unloosened from the end of the truck. The movement of the truck is then accomplished by the turning of the hand-wheel, revolving of the operating-rod, and winding of the chains upon 85 said rod, as previously described. After having been rolled or moved upon the platform the chains may, if so desired, be disconnected from the truck and the same allowed to remain upon the platform, where it may be unloaded at pleasure or removed to store-houses.

Having thus fully described my invention, what I claim as new, and desire to secure protection in by Letters Patent of the United States, is—

1. The combination, with a platform-car provided with transverse tracks, the end ones thereof being curved and the intermediate ones flat, and also provided with laterally-extending side keepers, of a transferable false top or truck fitting upon said car and provided on its under side with wheels or rollers, the end wheels being grooved and the intermediate wheels having flat peripheries, said transferable truck being also provided with side 105 notches, and uprights or vertical retaining-bars fitting in the notches of the top and having their lower ends passing into the keepers, substantially as set forth.

2. The combination, with a platform-car provided with transverse tracks located upon the top thereof, of a transferable false top or truck fitting upon said car, having transversely journaled upon its under side suitable wheels or rollers, which move upon the cross-tracks, substantially as and for the purpose set forth.

3. The combination, with a platform-car provided with transverse tracks, of a transferable false top or truck fitting upon said car, provided on its under side with a series of longitudinal parallel strips, transverse strips intersecting said longitudinal strips at suitable intervals, and short shafts journaled between said transverse strips and carrying 125 suitable rollers or wheels, substantially as set forth.

4. The combination, with a platform-car provided with suitable cross-tracks, of a transferable false top or truck fitting upon said car, and having transversely journaled upon its under side suitable wheels or rollers, which move upon the cross-tracks, and end chains connecting the car with the transferable top,

whereby the latter may be allowed lateral movement for dumping purposes and prevented from rolling off the car, substantially as set forth.

- 5 5. The combination, with a platform-car provided with tracks located upon the top thereof, of a transferable false top or truck fitting upon said car, and having journaled upon its under side suitable rollers or wheels moving 10 upon said tracks, operating-levers passing longitudinally beneath the car and provided on opposite ends with suitable hand-wheels, and chains connected to each of the operating-levers and extending laterally from the 15 same over pulleys journaled in the side pieces of the car, and thence inwardly beneath the transferable top, the ends of said chains being connected to opposite edges of the transferable top, substantially as set forth.
- 20 6. The combination, with a platform-car, of a transferable false top or truck fitting thereon, operating rods or levers passing longitudinally beneath the car and provided on opposite ends with suitable hand-wheels, 25 chains connected to each of the operating-levers and extending laterally from the same

over pulleys journaled in the side pieces of the car and then inwardly beneath the transferable top, the ends of said chains being connected to opposite edges of the transferable top, and a hand-lever fitting in holes 30 formed in the peripheries of the hand-wheels, substantially as set forth.

7. The combination, with a platform-car having its side edges provided with laterally-extending keepers, and also provided with end apertures or holes, of a transferable top or truck having end apertures registering with the apertures of the top or truck and provided with side notches, bolts passing 35 through said registering apertures, a key for locking said bolt beneath the car, and uprights or vertical retaining-bars fitting in the notches of the top and having their lower ends passing into the keepers, substantially 40 as set forth.

In testimony whereof I affix my signature in presence of two witnesses.

CHARLES WALKER JONES.
